HOUSING FOR EARTH BORING APPARATUS

Carter K. Reh, Van Nuys, Calif., assignor to Borg-Warner Corporation, Chicago, Ill., a corporation of Illinois

Application November 22, 1954, Serial No. 470,176

6 Claims. (Cl. 255—4.8)

The present invention relates in general to earth boring apparatus and is particularly concerned with vibration generating devices of the general type used to actuate a vibratory earth boring drill rod of the type disclosed in the patent to A. G. Bodine 2,554,005.

The principal object of the present invention is to provide an improved housing structure for enclosing a vibration generator of the type used for actuating a vibratory earth boring drill rod.

A more specific object of the present invention is to provide a housing structure of the foregoing general type comprising a plurality of complementary housing members adapted to be fitted together after the generator assembly is first mounted within one of the members.

More specifically, it is an object of the present invention to provide improved means for sealing a pair of complementary housing sections so as to prevent the admission of foreign particles thereto.

In connection with the foregoing object of the present invention, each of the housing sections is provided with a mating surface in which are provided opposed openings adapted to receive mounting shafts for facilitating the mounting of apparatus within the housing. Suitable resilient substantially incompressible plugs are disposed in the ends of the openings for sealing the openings against mud fluid customarily utilized in oil well drilling operations with which the present invention is particularly suited. Further, one of the mating surfaces of the complementary housing sections is provided with an elongated groove extending therearound and in order to provide an effective seal all the way around both of the housing sections, an elongated resilient substantially incompressible sealing member is disposed in this groove and passes through the incompressible plugs in such a manner that it is compressed against the other member when the mechanism is being assembled.

The foregoing and numerous other objects and advantages of the present invention will become apparent from the following detailed description thereof when read in conjunction with the accompanying drawings, wherein:

Fig. 1 is a schematic illustration of conventional oil well drilling apparatus utilized for suspending drill pipe string in an earth bore;

Fig. 2 is a schematic illustration of an earth boring drill rod of the type disclosed in the aforementioned Bodine Patent No. 2,554,005 and with which the present invention is particularly applicable;

Fig. 3 is a schematic elevational view of a vibration generator enclosed in a housing constructed in accordance with the principles of the present invention;

Figs. 4A, 4B and 4C comprise elevational views, shown partly in section, illustrating the features of the present invention;

Fig. 5 is a sectional view taken substantially along the line 5—5 in Fig. 4A and looking in the direction of the arrows;

Fig. 6 is a sectional view taken substantially along the

2

line 6—6 in Fig. 4A and looking in the direction of the arrows;

Fig. 7 is a sectional view taken substantially along the line 7—7 in Fig. 4B and looking in the direction of the arrows;

Fig. 8 is a sectional view taken substantially along the line 8—8 in Fig. 4C and looking in the direction of the arrows;

Fig. 9 is a fragmentary sectional view taken substantially along the line 9—9 in Fig. 4C and looking in the direction of the arrows;

Fig. 10 is a perspective view of one of the sealing plugs and the elongated sealing member passing through the plug; and

Fig. 11 is a sectional view of one of the sealing plugs with means associated therewith for applying an initial compression to the sealing plug for insuring effective sealing therearound even though surrounding mud fluid pressures are relatively low.

In oil well drilling operations utilizing drilling equipment of the type disclosed in the aforementioned Bodine patent, it is necessary to provide a vibration generating device or oscillator capable of vibrating the massive drill rod disposed at the lower end of the drill pipe string at substantially the resonant vibration frequency of the drill rod. As a practical matter, it is very difficult to provide such a vibration generator which is isolated from the flowing mud fluid that is pumped down the drill pipe string in order to drive a motor for actuating the vibration generator and to wash away earth formation fragments loosened at the bottom of the earth bore by a drilling bit fastened to the lower end of the vibratory drill rod. Therefore, one of the desirable features of the present invention resides in the unique vibration generator housing construction disclosed herein.

Referring now specifically to the drawings, wherein like reference numerals in different views identify identical parts, it is contemplated that the drill rod having a vibration generator, such as is disclosed herein, will be suspended at the lower end of a drill pipe string in an earth bore hole with the drill pipe string being supported by a derrick such as is disclosed in Fig. 1 of the drawings. This derrick for supporting the drill pipe string and vibratory drill rod is conventional in oil well drilling operations and includes a derrick 10, draw works 11, driving rotary table 12, kelly 13 extending through table 12, swivel 14 coupled to the upper end of the fluid passage through kelly 13 and hook 15 supporting the bail of swivel 14. The hook 15 is suspended through a travelling block 16 and cable 17 from the top of the derrick 10 and the cable 17 is wound on the usual hoisting drum of the draw works 11. Mud fluid, such as is conventionally employed in oil well drilling operations, is pumped from a supply tank or sump 19 and is delivered under pressure by pumps 20 through a pipe 21 and hose 22 to the goose-neck of swivel 14, and from this point the mud fluid flows down through the kelly 13 and into and through a drill pipe string 23 coupled to the lower end of the kelly 13.

The kelly 13 and drill pipe string 23 extend into a bore hole 24 which extends downwardly into the earth. The bore hole 24 is lined or cased for a suitable distance down from the ground surface by surface casing 25 which is supported by a landing flange 26 resting on a concrete footing 27 in the bottom of a pit 28. A blow-out preventer 29 is mounted at the head of the casing 25 and a riser 30 above the blow-out preventer 29 is provided with a mud flow line or delivery pipe 31. The mud flow line 31 is shown as discharging onto a conventional vibratory mud screen 32, and the mud is led from the latter back to the sump 19 by means of a pipe line 33.

The drill pipe string 23 coupled at the lower end of kelly 13 comprises a conventional drill pipe string made up of a number of drill pipe lengths 34 which may be coupled together by the usual tool joints. The drill pipe string 23 includes a massive elongated vibratory drill rod 35 connected to the lower end of the pipe string 23, with the drill rod 35 being provided with an earth cutting bit 36 at the lower end thereof. The vibration generator comprising the subject matter of the present invention is disposed at the upper end of the vibratory drill rod 35 and is indicated generally by reference numeral 37.

The vibration generator 37 is fastened at the top end thereof to a driving turbine indicated generally by reference numeral 38 and shown only fragmentarily herein. The connection to the turbine 38 is by means of a joint comprising a plurality of bolts 39 extending vertically through a flange 40 and into a flange 41 at the lower end of the turbine housing.

The vibration generator or oscillator 37 is mounted within a housing which will now be described in detail. This housing comprises a pair of complementary substantially semicylindrical elongated housing members 42 and 43. These housing members 42 and 43 are enclosed within an outer enclosing cylindrical member 44 and between the outer member 44 and inner housing members 42 and 43 are suitable passages for permitting mud fluid pumped down into the bore hole 23 by the mud pumps 29 to pass by the oscillator 37.

The cylindrical enclosing member 44 is threaded to the housing members 42 and 43 at its upper end, as indicated at 45, and at the lower end an internal nut 46 is threaded into the enclosing cylinder 44, as indicated at 47, to hold the structure integral. Suitable bolts or screws 48 similar to the bolts 39 are screwed through a flange 49 formed at the upper end of the sub 34 disposed immediately beneath the oscillator 37 and these bolts pass through the internal nut 46 and are threaded into the lower end of the housing members 42 and 43.

At the upper end of the housing members 42 and 43 they are cut away for the purpose of receiving a driving shaft 50 which leads from and is driven by the turbine 38. Suitable pilot bearings 51 are located at the upper end of the shaft 50 with needle bearings 52 being provided at the lower end of the shaft for maintaining the concentric alignment of the shaft 50 within the housing members 42 and 43. The housing members 42 and 43 are cut away as indicated at 53 for receiving the pilot bearings 51 and are cut away as indicated at 54 for receiving a spacer sleeve 55. Below the spacer sleeve 55 the housing members 42 and 43 are cut away for the purpose of receiving the needle bearing 52. An inwardly projecting flange 56 provides an abutment for the outer race for the needle bearings 52 while the spacer sleeve 55 serves to fix the longitudinal position of the outer race of needle bearing 52. A pair of snap rings 57 and 58 are respectively disposed between the sleeve 55 and the lowermost bearing 51 and between the uppermost bearing 51 and an inwardly projecting shoulder 59 formed on each mounting member 42 and 43. It is therefore apparent that the bearings 51 and 52 and sleeve 55 are all fixed longitudinally within the mounting members 42 and 43.

The inner race of each bearing 51 and 52 is firmly fixed to the outer periphery of shaft 50 and thus the bearings serve to pilot the shaft within the housing members 42 and 43.

At the lower end of the shaft 50 it is hollowed out as indicated at 60 and it has an outwardly projecting flange 61 thereon. A driving bevel gear 62 is secured to the flange 61 by means of a plurality of bolts 63.

The two mounting members 42 and 43 are respectively provided with a pair of mating surfaces designated respectively by reference numerals 64 and 65. The mating surface 64 on housing member 65 is provided with an elongated groove 66 on the right side as viewed in Figs. 4A, 4B and 4C and grooves 67 on the left side as

viewed in Figs. 4A, 4B and 4C. The grooves 66 and 67 connect with a similar groove 68 formed in the surface 69 of an end member 70 which is rigidly mounted at the lower end of mounting member 42. The surface 69 of member 70 mates against a surface 71 formed on a member 72 similar to the member 70 and integrally secured at the lower end of mounting member 43. An elongated resilient substantially incompressible sealing member 73 is disposed within the grooves 66, 67 and 68 and when the two mounting members 42 and 43 are tightened together by means of a plurality of bolts 74 arranged all along the longitudinal edges of said mounting members an effective seal is provided between the members 42 and 43. The mounting members 42 and 43 are cut away to provide a cavity 75 for housing the vibration generator elements which comprise four eccentrically mounted weights 76. Each of the weights 76 is fixed to a sleeve member 77 by means of a plurality of bolts 78 and each of the sleeve members 77 is integrally formed with a gear 79 thereon. The sleeves 77 are adapted to fit snugly around inner sleeve sections 80 and 81 having integral bearing surfaces 82 and 83 rotatably mounted on a supporting shaft 84. The sleeve sections 80 and 81 are each formed with a radially outwardly extending flange 85 which serves to retain the sleeve 77 therebetween. Suitable spacer washers 86 are disposed around the shaft 84 within cut-away portions 87 thereof and abut against the inside of the housing sections 42 and 43 in order to maintain the proper spacing of the sleeves 82 and 83.

The gear 79 is driven by a gear 88 secured to a shaft 89 having a bevel gear 90 thereon which is in continuous mesh with driving bevel gear 62. The shaft 89 is formed with shoulders 91 and 92 at either end thereof and these shoulders 91 and 92 respectively abut against the inner races of a pair of thrust bearings 93 and 94. The gear 79 which drives weight 76 is in continuous mesh with a gear 95 which is fastened to the next lower weight 76 for continuously driving the latter weight 76. The gear 95 meshes with an idler gear 96 which is concentrically mounted on a bearing sleeve 97 rotatable about a supporting shaft 98. The bearing sleeve 97 and gear 96 are fixed axially on the shaft 98 by means of a pair of thrust washers 99 and the thrust washers 99 are in turn held against axial displacement by means of a pair of split rings 100 which fit within suitable peripheral grooves formed around shaft 98.

The idler gear 96 in turn meshes with a gear 101 adapted to drive the third weight 76 and the gear 101 meshes with a gear 102 which drives the lowermost weight 76.

No further details regarding the construction of the weights 76 and gearing for driving the weights will be described herein as it is well-known that, with this arrangement of weights and driving gears, upon driving the series of weights, vertical forces tend to add and horizontal forces compensate for each other. Accordingly, the oscillator 37 generates vertical vibrations with a minimum of horizontal components.

To more thoroughly understand the manner in which the oscillator 37 generates the vibration forces, reference should be had to Fig. 3, wherein it is assumed that the gear 88 rotates in a clockwise direction. The top weight 76 and its driving gear 79 will therefore be driven in a counterclockwise direction and the second weight 76 and its driving gear 95 will be driven in a clockwise direction. Idler gear 96 will be driven in a counterclockwise direction and the third and fourth weights 76 will respectively be driving in clockwise and counterclockwise directions.

It will be assumed that the weights are arranged as shown in Figs. 4A, 4B and 4C so that during the first increment of rotation of the weights there will be a component of force in an upward direction developed by each of the weights. At the same time, there will be components of force to the right generated by the top and bottom weights

76 and these horizontal components to the right will be exactly counteracted by equal and opposite horizontal components of force to the left developed by the second and third weights 76. As a result, there will be no turning couple developed by the oscillator 37 which would tend to generate horizontal vibrations.

As will be apparent from Figs. 4A, 4B and 4C and Fig. 6, each of the housing sections 42 and 43 is formed with a plurality of semi-cylindrical cavities 103 for receiving the supporting shafts 84 for each of the weights and the supporting shaft 98 for the idler gear 96 as well as suitable cavities 104 and 105 for receiving the thrust bearings 93 and 94. The housing section 42 is provided with grooves 106 and 107 on the face 64 thereof adapted to mate with face 65 of housing section 43. Each of these grooves communicates with the cavities 103 and the groove 106 communicates with groove 104 while groove 107 communicates with cavity 105. A pump 108, to be described hereinafter, supplies oil under pressure through the grooves 106 and 107 for lubricating the various mounting shafts 84, 98 and 89 for the different gears of the oscillator.

Each of the mounting shafts 84 is provided with a pair of peripheral grooves 109 disposed at either end thereof and these grooves communicate with one or more radial passages 110 which, in turn, communicate with a central axial passage 111. The central passage 111 communicates with a plurality of radially extending passages 112 leading to the outer surface of the shaft 84. The inner bearing sleeve members 80 and 81 are each provided with internal peripheral grooves 113. Thus, fluid under pressure is pumped through the lines 106 and 107 into the peripheral grooves 109 and through passages 110, 111 and 112 to peripheral grooves 113 formed on the inner bearing surfaces of the sleeve bearings 80 and 81. The oil thus seeps axially from the peripheral grooves 113 in order to lubricate the bearing surfaces of the shaft 84 and the sleeve bearings 80 and 81.

The supporting shaft 98 for the idler gear 96 is provided with peripheral grooves 114 which communicate with the elongated grooves 106 and 107. The peripheral grooves 114 in turn communicate through a plurality of radial passages 115 which communicate with an axial passage 116 connected with radial passages 117 leading to the exterior of the shaft 98. Thus, oil is supplied to the bearing surfaces of the shaft 98 and the sleeve bearing 97 for lubricating these surfaces.

The thrust bearings 105 and 104 are in direct communication with the grooves 106 and 107 and thus oil pressure is supplied to these bearings for properly lubricating them. The groove 106 extends upwardly to the turbine 38 as indicated. The groove 107 leads to the interior of the housing as indicated by openings 118 and excess oil above that required to lubricate the various shafts and thrust bearings is allowed to drip down through the oscillator and maintain a proper amount of lubricant on the meshing gears.

The pump 108 may be of any well-known type, such as the internal-external gear type or mating external gear type, for example, and is driven by a gear 120 which continuously meshes with the gear 102. The pump 108 draws oil from a sump 121 formed when the housing sections 42 and 43 are fastened together. The oil drawn from the sump 121 is pumped out through a pump outlet 122 which communicates with an external peripheral groove 123 extending around a base 124 of the pump 108. The output oil acts against a pressure regulator valve 125 comprising a ball check 126 held against a valve seat 127 by means of a compression spring 128. When the output pressure of the oil exceeds the value of the oil pressure necessary to unseat the ball check 126 from the seat 127, excess fluid passes out through a passage 129 which communicates with an external peripheral groove 130 formed on member 124. The groove 130 communicates with a plurality of passages 131 leading to

a pair of radiator assemblies 132. The radiator assemblies 132 comprise thin walled metal members which are disposed along opposed sides of the sump 121. The radiators 132 communicate with the sump 121 through a plurality of passages 133 and convey the excess fluid back into the sump 121.

An oil strainer 135 is disposed within the sump 121 and an input pipe 136 leading to the pump 108 is positioned within the strainer 135. A plurality of baffles 137 each having holes 138 therein are located in the sump and these baffles serve to prevent the oil in the sump from splashing and foaming to an undesirable degree.

In order to seal the ends of the semi-cylindrical cavities 103 and 105, a plurality of resilient substantially incompressible plugs 140, which may be made of rubber or some similar material, are disposed within the cavities. Each of these plugs is provided with a central aperture 141 and is cut, as at 142, for enabling the positioning of sealing member 73 in the opening 141. The plugs 140 are adapted to fit snugly within the cavities and when the housing members 42 are sealed together by tightening the bolts 74, the sealing member 73 and the plugs 140 tightly seal the entire cavity. When the oscillator is in operation, mud fluid pressure of the order of several thousand p. s. i. acts against tapered surfaces 143 at the outer ends of plugs 140 tending to compress the plugs more tightly against the cavity walls and thus effect a better seal.

In Fig. 11 means are shown for effecting an initial seal of the plugs 140 and this means comprises a pressure disc 144 adapted to act against the tapered surfaces 143. A threaded screw 145 having a nut 146 threaded therearound is positioned with the nut 146 behind a stop washer 147. When the screw 145 is turned, it compresses the pressure plate 144 against the plug 140 to provide an initial compression of the tapered walls 143 against the confining walls of the cavity 103.

From the foregoing description of the present invention it is apparent that it provides an improved vibration generator housing incorporating features enabling ease of assembly and which facilitate sealing of the housing against severe external pressures. It is contemplated that the presently disclosed oscillator housing will be capable of sealing out mud fluid at pressures of up to several thousand pounds per square inch.

It is contemplated that numerous changes and modifications may be made in the present invention without departing from the spirit or scope thereof.

What is claimed is:

1. A housing for a vibration generator having a plurality of rotary vibration generating elements, said housing comprising a pair of complementary substantially semi-cylindrical housing members having surfaces adapted to mate with each other and thereby provide a substantially cylindrical housing, means providing a seal between the mating surfaces of said housing members, means providing facing openings in said mating surfaces and diametrically opposed to each other for mounting supporting shafts for said vibration generating elements, and sealing means for the outside ends of said openings comprising resilient substantially incompressible plugs.

2. A housing for a vibration generator having a plurality of rotary vibration generating elements for vibrating a massive vibratory earth boring drill rod, said housing comprising a pair of complementary substantially semi-cylindrical housing members having surfaces adapted to mate with each other and thereby provide a substantially cylindrical housing, means providing a seal between the mating surfaces of said housing members, said housing members being provided with facing openings in said mating surfaces diametrically opposed to each other for mounting supporting shafts for said vibration generating elements, an enclosing cylindrical member disposed around said housing members and to

gether with said housing members including means defining longitudinally extending passages for conveying pressurized mud fluid therethrough, and sealing means for the outside ends of said openings comprising resilient substantially incompressible plugs for sealing out the mud fluid from said housing.

3. A housing for a vibration generator having a plurality of rotary vibration generating elements for vibrating a massive vibratory earth boring drill rod, said housing comprising a pair of complementary substantially semi-cylindrical housing members having surfaces adapted to mate with each other and thereby provide a substantially cylindrical housing, means providing a seal between the mating surfaces of said housing members, said housing members including means defining facing openings in the mating surfaces thereof and said openings being diametrically opposed for mounting supporting shafts for said vibration generating elements, an enclosing cylindrical member disposed around said housing members and together with said housing members including means defining longitudinally extending passages for conveying pressurized mud fluid therethrough, and sealing means for the outside ends of said openings comprising resilient substantially incompressible plugs for sealing out the mud fluid from said housing.

4. A housing comprising a pair of complementary substantially semi-cylindrical members having surfaces adapted to mate with each other and thereby provide a substantially cylindrical housing, said semi-cylindrical members including means defining pairs of facing openings in the mating surfaces thereof and the openings of each pair being diametrically opposed for mounting shafts in said housing, and means for sealing said members together and comprising resilient substantially incompressible plugs adapted to be tightly fitted in the outer ends of said openings, one of said mating surfaces being formed with an elongated groove extending therearound, said plugs being formed with central apertures adapted to be disposed in alignment with said groove when the plugs are disposed in said openings, and an elongated resilient substantially incompressible sealing member disposed in said groove and extending through said apertures for providing a seal between said semi-cylindrical members.

5. A housing comprising a pair of complementary members having surfaces adapted to mate with each other to provide an enclosed housing for mounting apparatus therein, said complementary members including means defining facing openings in the mating surfaces thereof for facilitating mounting said apparatus in the housing,

and means for sealing said complementary members together and comprising resilient substantially incompressible plugs adapted to be tightly fitted in the outer ends of said facing openings, one of said mating surfaces being formed with an elongated groove extending therearound, said plugs being formed with generally centrally located apertures adapted to be disposed in alignment with said groove when the plugs are disposed in said facing openings, and an elongated resilient substantially incompressible sealing member disposed in said groove and extending through said apertures for providing a seal between said complementary members.

6. A housing for a vibration generator having a plurality of rotary vibration generator elements for vibrating a massive vibratory earth boring drill rod, said housing comprising a pair of complementary substantially semi-cylindrical housing members having surfaces adapted to mate with each other and thereby provide a substantially cylindrical housing, said complementary members including means defining facing openings in the mating surfaces thereof for mounting supporting shafts for said vibration generating elements, an enclosing cylindrical member disposed around said housing members and together with said housing members including means defining longitudinally extending passages for conveying pressurized mud fluid therethrough, and means for sealing said complementary members together for preventing the admission of the mud fluid thereinto and including resilient substantially incompressible plugs adapted to be tightly fitted in the outer ends of said facing openings, one of the mating surfaces being formed with an elongated groove extending therearound, said plugs being formed with generally centrally located apertures adapted to be disposed in alignment with said groove when the plugs are disposed in said facing openings, and an elongated resilient substantially incompressible sealing member disposed in said groove and extending through said apertures for providing a seal between said complementary members for sealing out the mud fluid from the vibration generating elements within the housing.
